UNITED STATES PATENT OFFICE.

CHARLES C. BROWN, OF ROWLETTS, KENTUCKY.

MAIL DELIVERING AND RECEIVING APPARATUS.

1,184,617.

Specification of Letters Patent.

Patented May 23, 1916.

Application filed December 8, 1915. Serial No. 65,827.

To all whom it may concern:

Be it known that I, CHARLES C. BROWN, a citizen of the United States, residing at Rowletts, in the county of Hart and State 5 of Kentucky, have invented new and useful Improvements in Mail Delivering and Receiving Apparatus, of which the following is a specification.

The present invention contemplates the 10 provision of a mechanism for delivering and receiving mail bags or the like at stations while the train is in motion, the primary object being to provide a mechanism of this character which is durable, positive and efficient in operation.

The nature and advantages of the invention will be better understood from the following description, when taken in connection with the accompanying drawings, the 20 invention residing in the construction, combination and arrangement of parts as defined in the appended claims.

In the drawings forming part of this specification like numerals of reference indicate similar parts in the several views and wherein:

Figure 1 is a perspective view showing both the car carrying mechanism and the station device. Fig. 2 is an end view, the 30 car being partly broken away. Fig. 3 is a view showing the inoperative position of parts of the car mechanism to the station device. Fig. 4 is a front elevation of the receiving fork and showing the discharge position of the bag carrying element. Fig. 5 is an enlarged detail sectional view through the track and movable arm. Fig. 6 is an enlarged view of the tracks and adjustable arm partly in section showing the locking 40 device.

Referring more particularly to the drawings in detail 5 indicates the car which carries a part of the mechanism for the purpose of delivering and receiving mail bags 45 at the station, while 6 indicates generally the station device that co-operates with the mechanism above mentioned.

Secured to the opposite sides of the car at points above the door openings therein, are 50 spaced superimposed tracks 7, between which is slidably fitted the arm 8, the latter having journaled on one end thereof a roller 9 to facilitate the adjustment of this arm, while the opposite end of the arm projects 55 through a suitable opening in one side of the car as shown. Fixed upon the outer end

of the arm 8 in any suitable manner, is a duplex fork 10, the members of the fork being oppositely curved to provide flared entrance passages for the reception of the bag 60 hangers 11 which are suspended from the station device as illustrated. The lower member of the fork is provided with the resilient elements 12 adjacent its opposite ends, which elements have one end spaced 65 from the fork member and beneath which the hangers 11 are held to prevent casual separation of the bag from the fork when received by the latter. Secured to the fork 10 and depending therefrom is a suitable 70 support 13, while journaled for free swinging movement upon the stud 14 projecting forwardly from the lower end of the support 13 is what I term a bag carrying member 15. This member can be of any suitable 75 construction, preferably consisting of an elongated body provided with a finger 16 at each side thereof and upon which the mail bags to be delivered at the station are suspended by means of a suitable hanger 17 as 80 illustrated.

With a view of maintaining the carrier 15 in an upright or operative position, so as to permit of the hanging of a bag thereon, I preferably make use of a leaf spring 18 having 85 one end secured to the support 13 and projecting forwardly therefrom. The spring is so positioned with relation to the carrier 15 when the latter is in operative position, as to overhang the carrier and engage in a 90 groove or recess 19 formed in the upper end thereof.

Arranged at a suitable distance from the track at each station along the route of the train, is positioned a post or upright 20, 95 upon which is pivoted a lever 21, carrying at its forward end a substantially diamond shaped plate 22, from the opposite end or ends of which the hangers 11 of the bags to be received by the fork 10 are suspended. 100 The lever with the plate normally assumes an upright position when not in use as clearly shown in Fig. 3, while projecting from the post 20 are the stop lugs 23 adapted to limit the pivotal movement of the 105 lever in one direction and support the lever in horizontal position under the weight of the bags as will be readily understood. Projecting centrally from the plate 22 is a tripping element 24 adapted to engage the carrier 15 to reverse the position of the carrier 110 from that shown in Fig. 1, to an inoperative

position such as shown in Fig. 3 subsequent to the release of the carrier from the spring 18, which is effected in the manner to be presently described.

5 Now, it will be manifest, that as the train approaches the station, and the station device is in the position illustrated in Fig. 1, the arm 8 is projected through the opening in the side of the car to inoperative position, the arm being provided with one or more stops 25 to limit the adjustment of the arm in this direction. Carried by the innermost end of the arm is a yoke member 26 embracing the track elements 7 and 10 serves as a guide for the arm as the latter is adjusted to operative or inoperative position. When mail bags are adapted to be delivered at the station, they are hung upon one of the fingers of the carrier 15, it of 15 course being understood that this element must first be locked in upright position by means of the spring 18 as clearly shown. As the train passes the station, the fork 10 is so positioned with relation to the plate 22 20 that the lower member of the fork passes through the hanger 11 removing from the plate 22 the mail bag carried by the hanger 11. As the train passes the station device, the spring 18 which projects a slight distance beyond the carrier 15 engages the upper edge of the plate 22, and by reason of the inclination presented by this edge, the spring 18 is released from the groove in the carrier 15, so that when the latter is struck 25 by the tripping element 24 it is swung upon its pivot to the position illustrated in Fig. 3, whereupon the bags to be delivered are dropped from the carrier to the ground simultaneously with the removal of the bags 30 from the plate 22 to be taken on the car. It might here be stated that a suitable latch mechanism 26 operates to hold the arm 8 in 35 either normal or projected position.

Positioned between the post 20 and the 40 track, is a shield 27 which may be pivotally connected with the ground or surface in any suitable manner, and held in operative or inclined position by means of a brace 28. The bags to be delivered at the station are 45 dropped from the carrier 16 upon the shield 27, the latter serving to prevent the bags from being sucked under the car.

While I have shown and described what I now consider the preferred embodiment of 50 the invention, I desire to have it understood that I do not limit myself to the exact construction and arrangement of parts herein illustrated, and that various changes may

be resorted to when desired as fall within the scope of the appended claims. 60

What is claimed is:—

1. A mail bag delivering and receiving apparatus comprising an arm normally positioned within a car and adjustable to be projected therefrom, a duplex fork carried 65 at one end of the arm, means for holding said arm in inoperative or projected position, a pivotally mounted bag carrier positioned in advance of said fork, and having a groove in one end thereof, a resilient locking element normally positioned in said groove for holding the carrier in bag carrying position, a station device including a plate adapted to be disposed in the path of movement of said resilient element and engaged thereby to effect a release of said carrier, and a tripping member carried by the plate for moving said carrier to a discharge position subsequent to its release. 70

2. A mail bag delivering and receiving 80 apparatus comprising spaced superimposed track members arranged within a car, an arm slidably fitted between said tracks and adapted to be projected from the car, a roller carried by one end of the arm, means 85 for guiding said arm in its movements, means for limiting the adjustment of said arm to projected position, means for locking said arm in either normal or operative position, bag carrying means at one end of 90 the arm, and a stationary tripping element adapted to move said bag carrier means to a discharge position, and to support the bags adapted to be received by the fork. 95

3. A mail bag delivering and receiving 100 apparatus comprising an arm normally positioned within a car and adjustable to be projected therefrom, bag carrying means on one end of said arm and including a pivoted bag carrying element, a resilient arm co-operating with said element to hold the latter in bag carrying position, a station device including a plate adapted to support the bags to be taken by said arm, said plate having angular surfaces to be engaged by 105 said resilient arm to effect a release of said element, and a tripping member carried by said plate for moving said element to discharge position subsequent to its release.

In testimony whereof I affix my signature 110 in presence of two witnesses.

CHARLES C. BROWN.
